FIG. 6

UNITED STATES PATENT OFFICE.

GEORGE D. LINO, OF DENVER, COLORADO.

SIGNATURE KEY.

Application filed February 23, 1927. Serial No. 170,097.

This invention relates to keys for locking devices, and has for its object to provide a novel construction and arrangement of the controlling edge, or edges.

5 The construction and arrangement of the controlling edge, or edges of present time keys to the very best of my knowledge have either bitted edges to adjust plungers, or straight line cut edges to pass certain pins 10 in the locks.

The great majority of people unskilled in the art of keymaking can obtain a keyblank, and with an ordinary file duplicate the present time keys, which state presents a constant 15 danger of dishonesty.

A better understanding of the invention can be had by referring to the accompanying description and drawings which form part 20 of this application, and in which

Fig. 1 shows a side elevation of a key with the controlling edge formed by the signature 25 of the key owner.

Fig. 2 shows a side elevation of a key with the controlling edge formed by a pass- 25 word.

Fig. 3 shows a side elevation of a key with the controlling edges formed on two sides of the key. Fig. 4 is an end view of Figure 1.

Fig. 5 shows a side elevation of a key constructed according to a modified form of the 30 invention.

Fig. 6 shows a top view thereof.

The key has the usual keybow 10, the usual 35 aperture 11, and the usual blade 12 which fits into the locking device.

The controlling edge, or edges 13 are formed by the upper outline of a written signature, a written password, etc. The controlling pins or plungers in the locking device may act against the points 14, 15, 16, etc., of the controlling edges, or may act 40 against a part, or the entire controlling edge.

A fraudulent person gaining possession of the key from the owner for a short time will 45 experience great difficulty in trying to duplicate the same. Since the controlling edge is continuously changing in direction line, it gives no hints as to where the pins or plungers are located in the locking device, and 50 therefore it would be necessary to duplicate the entire outlines of the signatures to make

a key that would operate the locking device. This would be an impossible task to the unskilled majority.

In the modified form of the invention illustrated in Figs. 5 and 6, the key blade 12 is formed along the top edge with a dove-tailed groove 20 longitudinal with the blade, and a pair of tapped apertures 21 transverse to the blade, and communicating with the dove-tailed groove. Engaged in the dove-tailed groove 20 is a dove-tail 22 formed on the bottom edge of a keyedge 23. The top edge of the keyedge 23 has a controlling edge formed by certain projections and depressions formed by a written signature 24, or the like, either countersunk in the keyedge as indicated by 25, or raised as indicated by 26. Engaged in the tapped apertures 21 are the set screws 27 which act to hold the keyedge 23 in place.

While I have illustrated and described my invention with some degree of particularity, I realize that in practice various alterations 75 therein may be made. I therefore reserve the right and privilege of changing the form of the details of construction without departing from the spirit or the scope of the appended claims.

Having thus described my invention, what I claim as new and desire to secure by United States Letters Patent is:—

1. In a device of the class described, a key blade formed along the top edge with a dove-tailed groove longitudinal to the blade, and 85 with a pair of apertures transverse to the blade, the apertures communicating with the dove-tailed groove, a keyedge formed on the bottom edge with a dove-tail engageable with the dove-tailed groove, certain projections 90 and depressions on the top edge of the keyedge, and set screws engaged in the said apertures.

2. In a device of the class described, a key blade formed along the top edge with a 95 groove, a keyedge slidably arranged in the groove, and means for releasably holding the said keyedge in place.

In testimony whereof I have affixed my signature.

GEORGE D. LINO.
